CIRCULATION AND EXPANSION JOINT FOR
WELL DEVICESReuben C. Baker, Coalinga, Calif., assignor to
Baker Oil Tools, Inc., Huntington Park, Calif.,
a corporation of California

Application July 25, 1939, Serial No. 286,405

12 Claims. (Cl. 166—1)

This invention relates to circulation and expansion joints employed in connection with well devices, such as cement retainers, which are lowered into the hole on a running-in string of tubing or drill-pipe to be set in the casing and disconnected from the string after the desired cementing or other operation has been performed. Disconnection of the string is usually effected by rotating it in the proper direction to uncouple the elements of a threaded joint securing it to the well device. But since the device is fixed to the casing, such unscrewing causes elevation of the mating threaded element on the tubing string and the corresponding raising of the whole string in the event that it is fixed to the elevated element. Invariably, binding at the detachable threaded joint occurs, due to the progressively increasing load placed on the threads as rotation of the string continues, occasioned by the relieving of the tension in the string and its resting on the joint.

The provision of a telescopic expansion joint in the string immediately above the well device obviates the aforementioned difficulty, permitting ease of rotation of the string and its ready disconnection. Moreover, specific flow features can be incorporated in the expansion joint to provide selective control of the paths pursued by drilling mud, cement slurry, or any other fluid with respect to the tubing, well device, and casing.

It is an object of the present invention to provide a circulation and expansion joint of the aforementioned character embodying improved selectivity features for controlling the paths of flow of fluid passing from a string of tubing or drill-pipe.

It is a further object of the invention to provide an improved valve mechanism forming part of a telescopic circulation and expansion joint.

The invention has other objects that will become apparent from a consideration of an embodiment shown in the drawing accompanying and forming part of the present specification. This form will now be described in detail, but it is to be understood that such detailed description is not to be taken in a limited sense, since the scope of the invention is best defined by the appended claims.

Referring to the drawing:

Figure 1 is a partial longitudinal sectional view of a circulation and expansion joint with its valve mechanism illustrated in open position;

Figure 2 is a view similar to Figure 1, with the valve mechanism shown in closed position;

Figure 3 is a transverse section taken along the line 3—3 of Figure 1; and

Figure 4 is an elevation of the invention in association with a well packer.

5 A circulation and expansion joint A is incorporated in a tubing string with its upper collar 10 threaded to a joint of tubing B, and with its lower mandrel 11 threadedly connected with a sub 12, which, in turn, is detachably secured to a well device in the form of a cement retainer C, this latter connection usually being effected by means of mating left-hand threads (not shown), so that right-hand rotation of the tubing string can produce disconnection of the sub from the cement retainer after the latter has been set in the casing.

10 The circulation and expansion joint consists of the abovementioned mandrel 11 having a plurality of splines 13 welded or otherwise secured thereto for cooperatively forming a telescopic connection with inwardly directed ribs 14 provided on the interior of a seat 15 threaded to a cylinder 16, whose upper end is attached to the collar 10 as by welding material 17. These parts permit 15 relative longitudinal movement between the mandrel 11 and the cylinder 16, but also provide a positive driving interconnection because of the engagement between the ribs 14 on the valve head and the splines 13 secured to the mandrel. It is 20 to be noted, however, that circumferential clearance 18 is allowed between the splines and ribs to permit passage of fluid therebetween in the performance of objectives later described.

25 A valve head 19 is threadedly attached to the upper end of the mandrel and has a depending skirt portion 20 spaced from the mandrel to form an annular pocket 21 capable of receiving the upper part of a sleeve 22 slidably mounted on the mandrel. The lower end of this sleeve rests on the splines 13 and is provided with a flange 23 30 carrying a retainer ring 24 to which one end of a packing sleeve 25 of rubber or the like is secured through the agency of their respective interlocking flanges 26, 27. Similarly, interlocking flanges 28, 29 secure the other end of the sleeve 35 to the valve skirt.

40 When operating under a no-load condition, the packing sleeve 25 assumes its normal position disposed inwardly from the walls of the cylinder 16, leaving an annular open passage 30 permitting fluid to pass from the interior of the collar 10, around the valve head 19 and packing, and through the circumferential spaces 18 between the splines and valve seat to the exterior of the 45 tubing string. Should the upper part of the valve 50

head 19 abut the collar, fluid could still pass from the interior of the latter member through auxiliary by-pass ports 31 extending through the valve head and into communication with the annular passage between it and the cylinder walls.

The taking of an upward strain on the tubing string after the well device has been set in the casing will move the collar 10, cylinder 16, and attached valve seat 15 upwardly to produce engagement between a tapered surface on the valve seat and an opposed surface on the sleeve flange 23, to cause upward sliding of the sleeve within the annular recess 21 and compression of the rubber packing element 25 between its retainers transversely into sealing engagement with the walls of the cylinder. With the parts in this relationship, the annular passage 30 is closed, fluid being prevented from circulating around the valve head and mandrel in the manner described above. Instead, this fluid can only pass downwardly through the valve mandrel 11, sub 12 and well device C for the performance of whatever operation is desired. Following the performance of this desired operation, the strain on the tubing can be relieved and the telescopic parts 11, 16 separated to permit the resiliency or elasticity in the packing sleeve 25 to elongate it to its normal position away from the cylinder, to open the annular passage 30 and allow fluid to pass through this passage and between the spaced inclined seating surfaces on the sleeve 23 and valve seat 15 to the exterior of the tubing string. Rotation of the tubing string can now effect an unscrewing of the sub 12 from the cement retainer C, allowing the former member to be moved upwardly without elevating the entire string, in view of the telescopic splined connection between the mandrel 11 and the valve seat 15 and cylinder 16 which permits the mandrel and its associated parts to be slidably received within the enclosing cylinder.

By the use of the circulation and expansion joint, not only is disconnection of the string from the well device made easy, but various other operations can be performed. For example, the fluid or cement slurry within the tubing can be bled off into the casing at any time simply by lowering the cylinder 16 with respect to the valve mandrel and its head 19 to allow passage of fluid between these parts. In the performance of a cementing operation, fluid preceding the cement can therefore be kept out of the formation or prevented from going behind the casing or liner when desired, and excess slurry can be dissipated easily.

The provision of a packing seal in the form of a sleeve adapted to be expanded radially into engagement with the walls of the cylinder provides a much greater sealing area than was heretofore obtained, and consequently, offers a greater degree of assurance that leakage of fluid through the circulation joint will not occur, especially under high pressure operating conditions. Not only is fluid prevented from leaking along the packing, but its escape is further prevented by the abutting surfaces 23a, 15a provided on the valve seat and sleeve flange, which cooperatively form an additional seal.

I claim:

1. A circulation and expansion joint adapted to be connected in a tubing string or the like, including an outer member, an inner member slidably splined to said outer member and forming an annular passage therewith, packing means carried by one of said members, and means for axially loading said packing means to decrease

its length and compress it into engagement with the cylindrical wall of the other of said members to bridge said annular passage and close the same.

2. A circulation and expansion joint adapted to be connected in a tubing string or the like, including an outer member, an inner member slidably splined to said outer member and spaced therefrom to form an annular passage, a packing sleeve carried by said inner member, and cooperative means on said members for axially loading said sleeve to decrease its length and compress it laterally into engagement with the inner cylindrical wall of the outer member upon relative longitudinal movement therebetween, whereby to close said passage.

3. A circulation and expansion joint adapted to be connected in a tubing string or the like, including an outer member, a mandrel slidably splined to said outer member and carrying a head spaced therefrom to define an annular passage, a packing sleeve fixed to said head and normally spaced from said outer member to permit flow of fluid through said passage, and means carried by both said member and mandrel to compress said sleeve into engagement with the outer member upon their relative longitudinal extensible movement.

4. A circulation and expansion joint adapted to be connected in a tubing string or the like, including a cylinder, an abutment fixed to said cylinder, a mandrel slidably splined to said abutment, a head fixed to said mandrel and spaced from said cylinder to define an annular passage, a packing sleeve carried by said head and normally spaced from said cylinder to permit flow of fluid through said passage, and means engageable with said abutment to compress said packing sleeve into sealing contact with the walls of said cylinder to close said passage at a point removed from said abutment.

5. A circulation and expansion joint adapted to be connected in a tubing string or the like, including a cylinder, an abutment fixed to said cylinder, a mandrel slidably splined to said abutment, a head fixed to said mandrel and spaced from said cylinder to define an annular passage, a sleeve slidable on said mandrel, a packing around said sleeve having one end secured to the head and its other end supported by said sleeve, said abutment being adapted to contact said sleeve and cause compression of said packing into sealing contact with said cylinder upon separating movement between said cylinder and mandrel.

6. A circulation and expansion joint adapted to be connected in a tubing string or the like, including a cylinder, an abutment fixed to said cylinder, a mandrel slidably splined to said abutment, a head fixed to said mandrel and spaced from said cylinder to define an annular passage, a sleeve slidable on said mandrel, a packing sleeve around said sleeve having one end secured to the head and its other end to a retainer ring carried by said sleeve, said abutment being engageable with said sleeve to move its retainer ring toward said head and compress said packing into sealing contact with said cylinder upon separating movement between it and said mandrel.

7. In a device of the character described, an outer member, an inner member slidable within said outer member and adapted to rotate therewith, packing means carried by one of said members and having an intermediate surface between its ends for sealing engagement with the other of said members, and means operable upon rela-

tive extensible movement of said members for applying longitudinal loading to the ends of said packing means to move the portion between said ends laterally and said intermediate surface into sealing engagement with the other of said members.

8. In a device of the character described, an outer member, an inner member slidably longitudinally within said outer member and adapted to rotate therewith, packing means carried by one of said members, means operable upon relative sliding of said members for axially loading said packing means to deform it transversely into sealing engagement with the other of said members, and means for positively limiting the extent of deformation of said packing means.

9. In a device of the character described, an outer member, an inner member slidably splined to said outer member, packing means carried by said inner member, means operable upon relative sliding of said members to decrease the length of said packing means and force it toward sealing engagement with said outer member, and means between said inner and outer members for positively limiting the extent to which the length of said packing means can be decreased.

10. A circulation and expansion joint adapted to be connected in a tubular string, including an outer member, an inner member slidable within said outer member and forming an annular passage therewith, packing means carried by one of said members, and means operable upon relative extensible movement between said inner and outer members for axially loading said pack-

ing means to decrease its length and compress it laterally into engagement with the cylindrical wall of the other of said members to bridge said annular passage and close the same.

5 11. A circulation and expansion joint adapted to form part of a tubular string, including an outer member, an inner member slidable within said outer member and spaced therefrom to form an annular passage, cooperable splines carried by said members and arcuately spaced from each other to form fluid passages communicable with said annular passage, a packing sleeve carried by said inner member, and cooperable means on said members for axially loading said packing sleeve to decrease its length and compress it laterally into engagement with the inner cylindrical wall of the outer member to close said annular passage.

10 12. A circulation and expansion joint adapted to form part of a tubular string, including an outer member, an inner member slidable within said outer member and forming an annular passage therewith, packing means carried by one of said members, and means for axially loading said packing means to decrease its length and compress it laterally into engagement with the other of said members to bridge said annular passage and close the same, said loading means comprising cooperable elements on said inner and outer members for providing an additional seal to prevent flow of fluid through said annular passage.
